UNITED STATES PATENT OFFICE.

MONTIE BLEVINS MINER, OF SAMPSON, OREGON.

FRICITION-SET.

No. 823,802.

Specification of Letters Patent.

Patented June 19, 1906.

Application filed July 12, 1905. Serial No. 269,296.

To all whom it may concern:

Be it known that I, MONTIE BLEVINS MINER, a citizen of the United States, and a resident of Sampson, in the county of Douglas and State of Oregon, have invented a new and Improved Friction-Set, of which the following is a full, clear, and exact description.

The invention has reference especially to a device for setting the friction-pin of hoisting-engine drums, although it is useful in other connections, as will hereinafter appear.

The object of the invention is to reduce as much as possible the friction incident to the operation of "setting" or moving the friction-pin in apparatus of the class referred to; and this end I attain by a peculiar arrangement of the head and box with certain anti-friction devices and the adaptation of other peculiar friction devices to coact between the actuating-screw, head, box, and friction-pin in such a manner as practically to absorb the friction between the moving parts, rendering the device more durable and easier of operation and increasing the mechanical efficiency of the hoisting-engine.

The invention resides in certain novel features of construction and arrangement of parts, which will be fully set forth hereinafter, and pointed out in the claims.

Reference is had to the accompanying drawings, which illustrate as an example the preferred embodiment of my invention, in which drawings like characters of reference indicate like parts in the several views, and in which—

Figure 1 is a perspective view showing one drum of an ordinary hoisting-engine and illustrating the application of my invention thereto. Fig. 2 is an enlarged section of the friction-set. Fig. 3 is a cross-section on the line 3-3 of Fig. 2, and Fig. 4 is a detail of the handle.

In Fig. 1, *a* indicates part of the bed of a hoisting-engine, and *b* one of the drums or the drum thereof, the shaft of which is mounted on the bed in bearings, one of which is illustrated at *c*.

In Fig. 2, *d* indicates the shaft of the drum, and *e* the usual friction-pin, which passes through the shaft and serves to operate the clutch for throwing the drum *b* into action. Attached to the shaft *d* is the box *f*, in the outer end of which is located the tubular portion *g'* of the head *g*. *h* indicates a means for holding the head *g* and its part *g'* stationary, which means may be of any desired sort.

i indicates the operating-screw, which is threaded in the tubular part *g'* of the head *g* and is provided with a handle *i'*, facilitating the operation of the screw. *i'* indicates studs on the end of the screw *i*, adapted to be engaged by a tool of any sort to facilitate adjusting the screw with reference to the handle. Operating between the head *g* and the outer wall of the box *f* and located within said box is an antifriction bearing means comprising a disk *k*, formed with radial openings *k'*, receiving antifriction-rollers *k'*. These rollers *k'* run against wear-plates *k''*, which are arranged one at each side of the disk *k* and bear, respectively, against the box *f* and the head *g*. These devices serve to take up the friction otherwise existing incident to the rotation of the box *f* on the head *g*. *f'* indicates a packing which surrounds the tubular part *g'* of the head *g* and is located in a cavity formed in the outer wall of the box *f*, the adjacent wear-plate *k* serving to hold the packing in place. Located in the box *f* at the inner side of the head *g* is a disk or wear-plate *l*, formed with openings *l'*, in which pins *g''*, projecting from the head, are loosely received, whereby to hold the disk *l* stationary with the head, but to permit the disk to move longitudinally of the shaft *d* independently of said head. *i''* indicates a button or bearing member which is engaged between the inner end of the screw *i* and the disk *l* to reduce the friction between these parts, due to the turning of the screw. Engaging the friction-pin *e* is a disk *m*, similar to the disk *l* and having openings *m'* receiving pins *f''*, projecting from the inner wall of the box *f*, thus allowing the disk *m* to move freely axially of the shaft *d*, but causing said disk to rotate continuously with the box and shaft. Located between the disks *l* and *m* is a carrier or cage-disk *n*, this disk being formed, as shown in Figs. 2 and 3, with openings *n'*, which receive antifriction-rollers *n''*, these rollers bearing against the disks *l* and *n* to reduce friction incident to the independent or relative rotary movement of said parts. The disk *m* engages the friction-pin *e*, and upon moving said pin axially of the shaft *d* the friction-pin will be moved to operate the clutch, as will be understood from the prior art.

In the operation of the apparatus, assuming that it is employed as a friction-pin set for hoisting-engines, when it is desired to move the pin *e* and set the friction-clutch

the handle *i'* should be operated to turn the screw *i*. The head *g* and its tubular end *g'* being held stationary by the device *h*, the screw *i* will thus be advanced toward the 5 friction-pin, pushing the parts from the position shown in Fig. 2 and causing the elements *l*, *n*, and *m* to move leftward, pushing ahead of them the friction-pin *e* and causing them to operate in the friction-clutch. This 10 will start the revolution of the drum *b*. When it is desired to arrest the movement of the drum, it is only necessary to reverse the direction of movement of the handle *i'*, thus 15 returning the screw to the position shown in Fig. 2 and allowing the disks *l*, *n*, and *m* to recede from their position to permit the return of the friction-pin. It will be observed that this arrangement provides effectually 20 for the elimination of practically all of the appreciable friction due to the operation of the parts, and it renders the friction-set more durable, since its parts do not wear so quickly, and also increases the mechanical efficiency of the engine by eliminating a certain 25 part of the friction thereof. It also is easier to operate, since the parts move more readily and with less vibration than in devices of the kind usually employed for this purpose.

30 Having thus described the preferred form of my invention, what I claim as new, and desire to secure by Letters Patent, is—

1. The combination with a shaft and a pin 35 movable through the same, of a box having connection with the shaft, a head located in the box and having an internally-threaded tubular portion projecting through the outer end of the box, means engaged with said tubular portion for holding the head against 40 rotation, an actuating-screw operating in the tubular portion of the head, antifriction bearing devices acting between the head and the outer end of the box, and antifriction bearing devices acting between the head and 45 said pin of the shaft.

2. The combination with a shaft and a pin 50 movable through the same, of a box having connection with the shaft, a head located in the box and having an internally-threaded tubular portion projecting through the outer end of the box, means engaged with said tubular portion for holding the head against 55 rotation, an actuating-screw operating in the tubular portion of the head, antifriction bearing devices acting between the head and the outer end of the box, antifriction bearing devices acting between the head and said pin of the shaft, and a packing acting between the tubular portion of the head and the outer 60 wall of the box, said packing being held in position by the first-named bearing devices.

3. The combination with a shaft and a pin 65 movable through the same, of a box having connection with the shaft, a head located in the box and having an internally-threaded

tubular portion projecting through the outer end of the box, means engaged with said tubular portion for holding the head against rotation, an actuating-screw operating in the tubular portion of the head, antifriction bearing devices acting between the head and the outer end of the box, antifriction bearing devices acting between the head and said pin of the shaft, the first-named bearing devices comprising a carrier or cage disk, bearing members held therein, and wear-plates at the sides of the carrier-disk, the wear-plates being engaged by said bearing members and engaging respectively with the head and the box.

4. The combination with a shaft and a pin movable through the same, of a box having connection with the shaft, a head located in the box and having an internally-threaded tubular portion projecting through the outer end of the box, means engaged with said tubular portion for holding the head against rotation, an actuating-screw operating in the tubular portion of the head, antifriction bearing devices acting between the head and said pin of the shaft, said second-named bearing members acting between the screw and pin comprising disks respectively engaged with the screw and pin, and having sliding connection respectively with the head and box, a cage or carrier disk located between the first-named disks, and bearing members held in the carrier-disks and engaged respectively with the first-named disks.

5. The combination with a shaft and a pin movable through the same, of a box having connection with the shaft, a head located in the box and having an internally-threaded tubular portion projecting through the outer end of the box, means engaged with said tubular portion for holding the head against rotation, an actuating-screw operating in the tubular portion of the head, antifriction bearing devices acting between the head and the outer end of the box, antifriction bearing devices acting between the head and said pin of the shaft, the second bearing members acting between the screw and pin comprising a disk juxtaposed to the head and having an opening therein, a pin attached to the head and loosely fitted in the opening, a second disk engaged with the said pin of the shaft and having an opening therein, a pin carried by the box and fitted loosely in the opening of the second-named disk, a carrier or cage disk bearing between the two disks first named, and bearing members held by the carrier-disk and engaged with the first-named disks.

6. The combination of a shaft, a pin axially movable therein, a box connected with the shaft, a head stationary relatively to the box, an actuating-screw operating in the

head, antifriction devices acting between the head and box, and antifriction bearing devices acting between the screw and pin.

7. The combination with the shaft of a hoisting-engine drum and a friction-pin movable through the shaft, of a box in connection with the shaft, a relatively stationary head, antifriction devices acting between the head and box, and means in connection with the head for actuating said pin, said means for actuating the pin comprising a screw threaded in the head, and antifriction bearing devices acting between the screw and pin.

15 8. The combination of a shaft, a pin axially movable therein, a box connected with the shaft, a head stationary relative to the box, an actuating-screw operating in the head, a disk for receiving the thrust of the screw, means for constraining the disk to

move with the head, a disk for transmitting the thrust to the pin, means for constraining said disk to move with the box, and antifriction devices between the head and the box, and between the disks.

25 9. The combination of a shaft, a pin axially movable therein, a box connected to the shaft, a head stationary relative to the box, an actuating-screw operating in the head, a disk for receiving the thrust of the screw, a disk for transmitting the thrust to the pin, and antifriction devices between the head and the box and between the disks.

30 In testimony whereof I have signed my name to this specification in the presence of 35 two subscribing witnesses.
